UNITED STATES PATENT OFFICE.

JOHN MACLEAN, OF TOLEDO, OHIO.

OPERATING MECHANISM FOR VACUUM-CLEANERS.

1,202,201.

Specification of Letters Patent.

Patented Oct. 24, 1916.

Application filed June 20, 1911, Serial No. 634,219. Renewed April 17, 1916. Serial No. 91,750.

To all whom it may concern:

Be it known that I, JOHN MACLEAN, a citizen of the United States, residing at Toledo, in the county of Lucas and State of Ohio, have invented certain new and useful Improvements in Operating Mechanism for Vacuum-Cleaners, of which the following is a specification.

My invention relates to improvements in vacuum cleaners, and has for its leading object the provision of an improved machine of this character in which a constant suction is maintained by the movement of a flexible diaphragm within the machine.

15 A further object of my invention is the provision of an improved vacuum cleaner in which a single readily cleaned receptacle will serve to receive and retain the dirt drawn in by the suction in both of the suction chambers.

20 Another object of my invention is the provision of improved manually operated mechanism for causing the operation of the suction created diaphragm and mechanism for shifting said diaphragm to operate in a constant direction while the direction of movement of the manually operated controlling member varies.

25 Other objects and advantages of my improved vacuum cleaner and driving mechanism therefor will be apparent from the following description taken in connection with the accompanying drawings and it will be understood that I may make any modifications in the specific structure shown and described within the scope of my claim without departing from or exceeding the spirit of the invention.

30 Figure 1 represents a side elevation of my complete vacuum cleaner. Fig. 2 represents a longitudinal sectional view of the handle and mechanism contained therein.

In the drawings, the numeral 1 designates the basal pan or receptacle of my improved cleaner, said pan having secured thereto the axle 2 of the supporting wheels 3 to permit the ready transportation or mobility of the cleaner and having secured at the front portion thereof the cleaner or 45 suction nozzle 4, the pan being further formed with a peripheral outwardly projecting flange 5 at its upper edge. Secured to the rear of said flange 5 is the hinge 6 which is also secured to the double suction chamber 50 of my cleaner. Said chamber comprises a lower casing 7 having an outwardly extend-

ing flange 8 which rests on the flange 5 of the casing 1, and a second inverted pan or casing 9 similar in size and shape to the casing 7 and having a co-extensive peripheral flange 10, between which is inclosed the suction diaphragm (not shown). The flanges 8 and 10 secure it by the bolts or rivets 12. Mounted upon said casing 9 is a casing 39 to which is connected the tubular handle 50 containing the sprocket chain 49, which passes around the guide shield 51 mounted within the handle 50. Said member 51 is rotatably mounted on the pin 52 secured in the furcations of the yoke 53, said yoke having an outwardly extending threaded rod 54 projecting through the cap 55 and having a wing-nut 56 engaged on its outer end and bearing against the cap plate 55, the adjustment of the nut 56 60 serving to regulate the tension of the chain 49. To prevent the turning of the yoke 53 within the tubular handle 50 form on said yoke the guide pin 57 which rides in the slot 58 of the handle. Slidably mounted on the tubular handle 50 is the sleeve 59 which is adapted to be manually grasped and reciprocated. Extending inwardly from the sleeve 59 through the slot 60 in the handle is a screw 61 having its inner end engaged 65 in the block 62 which is provided with the passages 63 and 64 in which the parallel portions of the sprocket chains are engaged. Pivoted between the ears 65 of the block 62 is a dog 66 normally pressed against the end of 70 the block by the curved blade spring 67, while between the ears 68 on the opposite end of the block 62 is pivoted the dog 69 normally against the block and over the passage 64 by the curve blade spring 70. 75

When the sleeve 59 is moved in one direction it will shift with it the block 62 and one of the dogs 66 or 69 will engage between the solid links of the sprocket chain and will force the chain to move with the block, 80 while the dog on the opposite end of the block will ride idly over the parallel portion of the chain. As the movement of the sleeve is reversed, the idly riding dog will then engage the other portions of the sprocket 85 chain while the formerly operated dog will move idly over the chain, and in this manner the chains will be moved in a constant direction, irrespective of the direction of movement of the operating sleeve. 90

I claim:

In a device of the class described, the com-

bination with a tubular handle, of a sprocket wheel mounted therein, a guide sheave mounted in the tubular handle, a sprocket chain passing around the sheave, a block 5 slidably mounted within the tubular handle and having a pair of passages formed therein through which the parallel portions of the sprocket chain pass, a sleeve slidably mounted exteriorly on the tubular handle, 10 said handle having a longitudinally extending slot formed therein, means projecting through the slot for securing the block to the sleeve, a spring pressed dog pivoted to one end of the block intermediate the passages 15 and adapted to engage the chain and lock the same to move with the block when the block and sleeve are shifted along the handle in one direction and to disengage the chain when the block is moved in the opposite 20 direction, and a second spring pressed dog pivoted to the other end of the block ex-

terior to the passages and adapted to engage the other portion of the chain and lock it to move with the block when the first mentioned dog is riding idly over the chain 25 and to ride idly over the chain when the first mentioned dog is lockingly engaging the chain, whereby the chain is locked to move with the block when the block is moved in either direction, but different 30 parts of the chain are locked to the block to cause the chain to be shifted in a constant direction irrespective of the direction of movement of the sleeve and block secured thereto. 35

In testimony whereof I affix my signature, in the presence of two witnesses.

JOHN MACLEAN.
